UNITED STATES PATENT OFFICE.

CHARLES H. CLARK, JR., OF NEW YORK, N. Y.

MECHANICAL TOY.

1,136,465.

Specification of Letters Patent. Patented Apr. 20, 1915.

Application filed February 4, 1915. Serial No. 5,988.

To all whom it may concern:

Be it known that I, CHARLES H. CLARK, Jr., a citizen of the United States, and residing at New York, in the county of New York and State of New York, have invented certain new and useful Improvements in Mechanical Toys, of which the following is a specification, such as will enable those skilled in the art to which it appertains to 10 make and use the same.

This invention relates to mechanical toy devices, and the object thereof is to provide an improved toy of this class which is designed to represent a golf player, and which 15 will also amuse both old and young, and which is simple in construction and may be easily manipulated and which is also comparatively inexpensive.

The invention is fully disclosed in the following specification, of which the accompanying drawing forms a part, in which the separate parts of my improvement are designated by suitable reference characters in each of the views, and in which:—

25 Figure 1 is a side view of my improved toy; Fig. 2 a front view; and, Fig. 3 a cross section on the line 3—3 of Fig. 1.

In the practice of my invention, I provide a base plate *a* on the front end portion of 30 which is mounted a figure *b* representing a golf player and rearwardly of the figure *b* the base plate *a* is provided with an upwardly directed support *c*, which is preferably inclined backwardly and through which 35 is passed a rod *d* provided at its rear end with a head *e* by which it may be rotated in the support *c*, and said head *e* may be connected with the rod *d* in any preferred way, or be formed integrally therewith, but as 40 shown in the drawing said head is provided with a sleeve *e*² through which is passed a screw *e*³ by which the head is secured to said rod.

The rod *d* ranges upwardly and forwardly 45 and the front end portion thereof passes through the top back portion of the figure *b* and comes out under, or below the chin or head of said figure and is provided with a downwardly directed front arm portion *d*², to the lower end of which is secured a block *f* which is preferably triangular in form and provided with upwardly and laterally directed arms *f*² which represent the arms of the figure *b* and which swing with 50 the block *f* in the operation of the de-

vice as hereinafter described. The block *f* is provided at its lower end with a cross head *g* which projects forwardly and through which is passed a golf club *h* which is made adjustable in the head *g* by means of a set screw *h*².

Mounted on the rod *d* forwardly of the support *c* is a clutch block *i* having a set screw *i*² by which it is made adjustable on said rod, slidably mounted on said rod between the clutch block *i* and the support *c* is a clutch member *j* provided with teeth *j*² adapted to enter corresponding recesses in the clutch block *i*. The clutch member *j*, or the body thereof, in the construction 70 shown, consists of a disk having a milled perimeter, and mounted between the clutch member *j* and the support *c* is a spiral spring *k*, one end of which is secured to said support and the other to said clutch member. 75

Mounted on and secured to the rod *d* between the support *c* and the head *e* is a ratchet disk *m* provided preferably on its lower side only with ratchet teeth *m*², and mounted transversely of the base plate *a* is 80 a flat spring arm *n*, one end of which is secured to one side portion of the base plate as shown at *n*², and the opposite side portion of said base plate is provided with a pivoted catch *o* adapted to engage the free end portion of the spring arm *n* as shown in Fig. 2 and to be released so as to free said arm shown in Fig. 3. The spring arm *n* is provided centrally thereof with a raised tooth, projection or pin *n*³ adapted to engage the 85 teeth of the ratchet disk *m*. The ratchet disk *m* is also provided at the top thereof with a forwardly directed stop pin or device *m*³, and the top portion of the support *c* is 90 cut out or cut away to form shoulders *c*² in connection with which the stop device *m*³ operates to limit the rotary movement of the ratchet disk *m* and the rod *d* in either direction. 95

In the operation of this device a ball is 100 placed in front of the figure or player *b* and in position where it will be struck by the head *h*³ of the golf club when a stroke is made, and in making all strokes except the "putting" stroke or strokes, the clutch member *j* is in 105 engagement with the clutch block *i* and the spring arm *n* is in the position shown in Fig. 3, in which the pin or tooth *n*³ engages the ratchet teeth on the disk *m*. In this position of the parts the rod *d* is turned by 110

means of the head *e* thereof so as to swing the club *h* to the right, after which the free end of the spring arm *n* is depressed so as to free the ratchet disk *m* and the spring *k* rotates the rod *d* to the left and swings the club *h* quickly to the left and the ball will be struck by the head *h³* of the club.

In the operation of "putting", or making the putting stroke or strokes the clutch member *j* is moved downwardly on the rod *d* and held out of engagement with the clutch block *i*, and the rod *d* is manipulated by hand in which operation the club *h* may be swung in both directions.

15 In the construction shown the clutch member *j* is provided with a sleeve *j³* which passes partially through the spring *k*, but this sleeve is not essential, and various changes in and modifications of the construction herein described may be made, within the scope of the appended claims, without departing from the spirit of my invention or sacrificing its advantages.

Having fully described my invention what 25 I claim as new and desire to secure by Letters Patent, is:—

1. A golf playing toy device, comprising a base provided on one end portion with a figure which represents the player and rearwardly of said figure with a raised support, a rotatable rod which passes through said support and through the top body portion of said figure and is provided forwardly of said figure with a downwardly and forwardly directed member provided at its lower end with a golf club holder, and means for operating said rod.

2. In a toy device of the class specified and adapted to represent a golf player, a base 40 provided on one end portion thereof with a figure which represents the player and rearwardly of which is an upwardly directed support, a rotatable rod passing through said support and the front end portion of which extends forwardly of said figure and is provided with a downwardly and forwardly directed member provided at its lower end

with a golf club, and means for operating said rod.

3. In a toy device of the class described and adapted to represent a golf player, said device comprising a base provided on its front end portion with a figure which represents the player and rearwardly of which is an upwardly directed support, a rotatable 55 rod mounted in said support and extending forwardly of the figure and provided at its front end with a downwardly directed member having a golf club, and said member being also provided at its lower end with upwardly and laterally directed arms, and means for operating said rod.

4. In a toy device of the class described and adapted to represent a golf player, a base provided in its front end portion with a 65 figure and rearwardly thereof with a support, a rotatable rod mounted in said support and extending upwardly and forwardly of the figure and provided at its front end with a downwardly and forwardly directed 70 member adapted to carry a golf club, a clutch device mounted on said rod rearwardly of said figure, another clutch member slidably mounted on said rod rearwardly of said clutch device, a spiral spring mounted on said rod between said clutch member and said support and secured to both, said rod being also provided rearwardly of said support with a ratchet disk and said base being provided rearwardly of said support 80 with a spring arm adapted to engage said disk, means for holding said arm out of engagement with said disk, and means for limiting the rotation of said disk in both directions.

In testimony that I claim the foregoing as my invention I have signed my name in presence of the subscribing witnesses this 1st day of February 1915.

CHARLES H. CLARK, JR.
